CLAIM

The ornamental design for a gas appliance ignition switch, as shown and described.

DESCRIPTION

FIG. 1 is a top perspective view of a new design for a gas appliance ignition module.

FIG. 2 is a bottom perspective view of FIG. 1.

FIG. 3 is a top plan view of FIG. 1.

FIG. 4 is a bottom view of FIG. 1.

FIG. 5 is a front elevation view of FIG. 1.

FIG. 6 is a rear elevation view of FIG. 1.

FIG. 7 is a right side view of FIG. 1; and,

FIG. 8 is a left side view of FIG. 1.

The broken lines in the drawing depict portions of the gas appliance ignition switch that form no part of the claimed design.

1 Claim, 5 Drawing Sheets
